UNITED STATES PATENT OFFICE.

AGNES R. LENZ, OF HUNTLEY, ILLINOIS.

HOSPITAL BED.

1,404,207.

Specification of Letters Patent. Patented Jan. 24, 1922.

Application filed October 18, 1920. Serial No. 417,686.

To all whom it may concern:

Be it known that I, AGNES R. LENZ, a citizen of the United States, and a resident of Huntley, county of McHenry, and State of Illinois, have invented certain new and useful Improvements in Hospital Beds, of which the following is a specification.

My invention relates to hospital beds and it has for its principal object the provision 10 of a new and improved form and arrangement by which a ready adjustment can be made of the bed proper to suit the needs of the patient, and by which a suitable place for a nurse to rest is provided.

15 Other objects will appear hereinafter.

The invention consists in the combination and arrangements of parts hereinafter described and claimed.

The invention will be best understood by 20 reference to the accompanying drawings forming a part of this specification, and in which,

Fig. 1 is an end view of my improved bed, showing in dotted lines the nurse's bed in 25 extended position;

Fig. 2 is a side view of the bed shown in Fig. 1 as seen from the right in said figure;

Fig. 3 is top plan view of my bed, partly broken away for clearness of illustration:

30 Fig. 3^a is an enlarged detail view, being a fragmentary view as seen at the line 3^a in Fig. 3;

Fig. 4 is a vertical cross section, being an 35 inside face view of the end portion of the frame of the nurse's bed, a supporting leg for such frame being shown in changed position in dotted lines;

Fig. 4^a is a vertical cross section taken on line 4^a—4^a in Fig. 4;

40 Fig. 5 is a view, partly in section, showing the crank means for operating the supporting legs of the nurse's bed;

Fig. 6 is a fragmentary view, part in section, as taken on lines 6—6 of Fig. 5;

45 Fig. 7 is an enlarged detail view as taken on line 7—7 of Fig. 3;

Fig. 8 is a view of the part shown in Fig. 7 as seen from the right in said figure; and

50 Fig. 9 is an enlarged detail view, being a cross section taken on line 9—9 of Fig. 3.

Referring to the drawings, 15 indicates a bedstead of any approved type having the frame of a spring-bed mounted or resting upon its horizontal bars. The spring-bed 55 in the construction shown comprises angle bars 16 mounted upon the upper ends of

standards 17 which in turn are mounted rigidly in position upon longitudinally extended bars 18. Reticulated supporting fabric 19 of any approved type is mounted between the cross bars 16, springs 20 being interposed in the usual manner.

As is best shown in Fig. 2, there are longitudinally extending strips 21 at opposite sides of the supporting fabric 19. Pivoted 65 upon the strips 21 upon a transverse axis, there are longitudinally extending auxiliary frame bars or strips 22 which are connected at their ends by an angle iron 23. Reticulated supporting fabric 24 is 70 mounted between the bars or strips 22, being connected to the cross bar 23 by means of springs 25 corresponding to the springs 20 above referred to. In the preferred construction, the reticulated supporting fabric 75 is formed of wires extending longitudinally and transversely in spaced relation. As is shown in Fig. 3^a, the longitudinally extending wires of the supporting fabric 24 are connected to one of the transversely extending wires of the fabric 19 by having their end portions coiled thereabout, the reticulated fabric 24 being thus pivotally connected with the reticulated supporting fabric 19. As is clearly shown in Fig. 2, mattresses 80 26 and 27 are laid upon the supporting fabric, the mattress 26 resting upon the supporting fabric 19 and the mattress 27 being supported by the fabric 24.

Means is provided for supporting the 90 auxiliary frame and the supporting fabric carried thereby in elevated inclined position. In the construction shown this means comprises arms 28 pivotally mounted at opposite sides of the framework, such arms being connected together by a rock-shaft 29, as is clearly shown in Fig. 3. In the construction shown, the arms 28 are formed integrally with the shaft 29, and eyes or handles 30 are also formed integrally with the 95 arms for turning the arms about the shaft 29. As is best shown in Fig. 7, the shaft 29 and the arms 28 formed therewith are pivotally mounted upon the framework by means of clips 31 of any approved type secured to the longitudinally extending strips 21. The arms 28 are effective for supporting the auxiliary frame and the mattress 27 carried thereby by reason of engagement with notches 32 formed in the bars or strips 22, 110 as is best shown in Fig. 2, the arrangement being such that the arms 28 may be moved in

- unison and be caused to engage the notches 32 by applying force to the eyes or handles 30. When desired, the engagement between the arms 28 and notches can be easily and 5 quickly broken so as to permit the mattress 27 to move downward out of its inclined elevated position. By the provision of a plurality of the notches 32, the mattress 27 is capable of adjustment at the desired angle.
- 10 Coming now to the means for providing an auxiliary bed for a nurse, 33 indicates transversely extending rods at the opposite end portions of the frame of the spring-bed above described. Mounted upon the 15 rods 33 so as to slide thereon, laterally with respect to the bed, there is an auxiliary frame comprising end bars 34 and longitudinally extending side bars 35 connected to the end bars 34 by means of brackets 36.
- 20 The means for mounting this auxiliary frame upon the rods 33 comprises channel bars 37 connected in inverted position with the cross bars 34, as is best shown in Figs. 2 and 4^a. As is shown in Fig. 1, the bars 25 33 are inclined slightly so as to permit the auxiliary frame to slide easily into position beneath the supporting fabric 19 of the first described frame, a stop 38 in the form of a collar and a set-screw being provided upon the rod 33 for limiting the inward movement of the frame thereon. As is shown 30 in Fig. 3, the auxiliary frame is provided with reticulated supporting fabric 39 of any approved type springs 40 being interposed between the edge of the fabric and the cross bars 34. A full length mattress 41 is supported by the reticulated fabric 39 of the auxiliary frame.
- 35 Means is provided for supporting the outer edge of the auxiliary bed when it is moved out so as to project laterally, as shown in dotted lines in Fig. 1. This means comprises legs 42 pivotally mounted upon the cross bars 34 of the auxiliary frame, one 40 of such legs being mounted at each end of the auxiliary frame. A longitudinally extending bar 43 is provided connecting the legs 42 at their lower end portions. As is best shown in Fig. 4, the legs 42 are adapted 45 to be folded upwardly so as to project along the cross bars 34 as shown in solid lines in said figure or so as to stand in vertical position as shown in dotted lines in said figure. Means is provided for moving the legs 42 into and out of supporting position and for 50 holding them in either of such changed positions. This means comprises a pair of links 44 and 45 for each of the legs 42, such links being pivotally connected together by a 55 pin 46 and having pivotal connection with the leg 42 and the cross bar 34. When the links 44 and 45 are straightened out into alignment with each other, the legs 42 are caused 60 to stand in their vertical supporting position. When the legs are to be raised out of

supporting position, links 44 and 45 are buckled upwardly with respect to each other, causing the legs 42 to swing inwardly and upwardly into the position shown in solid lines in Fig. 4. The means for buckling 70 the links 44 and 45 upwardly comprises a longitudinally extending rod 47 extending between the links 44. The rod 47 is provided with a bracket 48 mounted thereon for providing a longitudinally extending slot 49, as 75 is best shown in Fig. 6. In the construction shown the bracket 48 is in the form of a heavy wire or rod having eyes 50 at its ends tightly embracing the rod 47 as is best shown in Fig. 5. A crank 51 extending between the side bars 35 of the auxiliary frame is provided, having a handle or lever 52 by which it is adapted to be operated. As is best shown in Fig. 6, the offset portion 53 of the crank 51 has a working fit in the slot 80 49, whereby upon a swinging motion of the crank the rod 47 is moved vertically with respect to the auxiliary frame. As the rod 47 is moved upward through the medium of the crank 51, the links 44 between which the rod 47 is mounted are also moved upwardly, serving to carry the legs 42 out of supporting position, as above described. Releasable means is provided for holding the crank 51 in turned position for maintaining the legs 42 in their raised position. This means in the construction shown comprises a spring clip 54 fixedly mounted upon the side bar 35 of the auxiliary frame.

While I have illustrated and described the 100 preferred form of construction for carrying my invention into effect, this is capable of variation and modification without departing from the spirit of the invention. I, therefore, do not wish to be limited to the 105 precise details of the construction set forth, but desire to avail myself of such variations and modifications as come within the scope of the appended claims.

Having described my invention, what I 110 claim as new and desire to secure by Letters Patent is:—

1. A hospital bed comprising a bedstead and a frame removably seated thereupon; reticulated supporting fabric carried by said 115 frame; a second frame mounted within said first named frame and slidably transversely thereof; means for supporting the outer edge of said second frame when moved out to extend laterally therefrom; and reticulated supporting fabric carried by said second frame.

2. A hospital bed comprising a bedstead and a frame removably mounted thereon; reticulated supporting fabric carried by said 125 frame; rods extending across said frame; a second frame slidably mounted on said rods and within said first frame and adapted to be projected laterally at one side; means for supporting the outer edge of said second 130

- frame when moved out to extend laterally therefrom; and reticulated supporting fabric carried by said second frame.
3. A hospital bed comprising a bedstead and a frame removably mounted on the horizontal bedstead bars; reticulated supporting fabric fixed upon the upper edges of said frame; rods extending across said frame below said fabric; a second frame; channel 10 pieces mounted in inverted position on said second frame and resting on said rods for mounting said second frame slidably in position within said first frame and above the bedstead bars; means for supporting the 15 outer edge of said second frame when moved out to extend laterally therefrom; and reticulated supporting fabric carried by said second frame.
4. A hospital bed comprising a removably mounted frame; reticulated supporting fabric carried by said frame; rods mounted on said frame near its opposite ends below said fabric; said rods being inclined downwardly from one side; a second frame 20 ably mounted on said rods and adapted to be held normally in position beneath the fabric on said first named frame by reason of the inclination of said rods; swingable means for supporting the outer edge of said 25 second frame when moved out to extend laterally therefrom; pivoted links for actuating said swingable means; a rod connecting said links; curved crank means to actuate said rod, links and swingable means into 30 and out of supporting position; and reticulated supporting fabric carried by said second frame.
5. A hospital bed comprising a bedstead and a frame removably mounted thereon; 40 reticulated supporting fabric fixed upon said frame; rods mounted on said frame near its opposite ends below said fabric; said rods being inclined downwardly from one side; a second frame slidably mounted on said rods 45 and adapted to be held normally in position beneath the fabric on said first named frame by reason of the inclination of said rods; stops on said rods for limiting the inward movement of said second frame with respect 50 to said first named frame; means for supporting the outer edge of said second frame when moved out to extend laterally therefrom; and reticulated supporting fabric carried by said second frame.
- 55 6. A hospital bed comprising a bedstead and a separate frame; reticulated supporting fabric fixed upon said frame; a second frame mounted on said first named frame and 60 slidably transversely thereof; supporting means movably mounted on said second frame adapted to be moved into position to support the outer edge of the second frame when projected laterally from said first named frame; and reticulated supporting 65 fabric carried by said second frame.
7. A hospital bed comprising a bedstead and a separate frame; reticulated supporting fabric carried by said frame; supporting standards on said frame for removably mounting it on the bedstead; a second frame 70 mounted between the standards on said first named frame and slideable transversely thereof; legs pivotally mounted on said second frame and adapted to be moved into position to support the outer edge thereof 75 when projected laterally from said first named frame; means for moving said legs in unison into supporting position; and reticulated supporting fabric carried by said second frame. 80
8. A hospital bed comprising a bedstead and a frame removably mounted thereon; reticulated supporting fabric fixedly mounted on said frame; a second frame mounted on said first named frame and slideable 85 transversely thereof; legs pivotally mounted on said second frame and adapted to be moved into position to support the outer edge thereof when projected laterally from said first named frame; means for moving 90 said legs in unison and for holding them either in their operative or their inoperative position; and reticulated supporting fabric carried by said second frame.
9. A hospital bed comprising a bedstead and a frame; standards fixed to said frame for removably mounting the same on the bedstead; reticulated supporting fabric fixed upon said frame; a second frame mounted on said first named frame and slideable transversely thereof; legs pivotally mounted on said second frame and adapted to be moved 100 into position to support the outer edge thereof when projected laterally from said first named frame; pivoted links connected between said frame and each of said legs adapted when the leg is in supporting position to brace the leg in position but adapted to be buckled with respect to each other for permitting the leg to be moved out of supporting position; and reticulated supporting 105 fabric carried by said second frame.
10. A hospital bed comprising a bedstead and a separate frame provided with cross bars; reticulated supporting fabric fastened to said cross bars; a second frame mounted between said first named frame and the horizontal bars of the bedstead, and slideable transversely on said first named frame; legs pivotally mounted on said second frame and 110 adapted to be moved into position to support the outer edge thereof when projected laterally from said first named frame; pivoted links connected between said frame and each of said legs adapted when the leg is in supporting position to brace the leg in position but adapted to be buckled with respect to each other for permitting the leg to be moved out of supporting position; means 115 for moving said links upwardly in unison.
- 120
- 125
- 130

- serving to raise said legs out of supporting position; and reticulated supporting fabric carried by said second frame.
11. A hospital bed comprising a bedstead 5 and a frame removably mounted thereon; reticulated supporting fabric fixedly mounted on said frame; a second frame mounted on said first named frame and slidable transversely thereof; legs pivotally mounted on 10 said second frame and adapted to be moved into position to support the outer edge thereof when projected laterally from said first named frame; pivoted links connected between said frame and each of said legs 15 adapted when the leg is in supporting position to brace the leg in position but adapted to be buckled with respect to each other for permitting the leg to be moved out of supporting position; means for moving said links upwardly in unison serving to raise 20 said legs out of supporting position; releasable means for holding said link-moving means at the limit of its motion for holding the legs out of supporting position; and reticulated supporting fabric carried by said 25 second frame.
12. A hospital bed comprising a frame; reticulated supporting fabric carried by said frame; a second frame mounted on said first 30 named frame and slidable transversely thereof; legs pivotally mounted on said second frame and adapted to be moved into position to support the outer edge thereof when projected laterally from said first named frame; 35 pivoted links connected between said frame and each of said legs adapted when the leg is in supporting position to brace the leg in position but adapted to be buckled with respect to each other for permitting the leg to 40 be moved out of supporting position; a rod

connecting the links of one leg with those of the other leg; a curved crank member transversely mounted on said second frame for moving said rod for actuating said links serving to carry the legs into and out of supporting position; and reticulated supporting fabric carried by said second frame. 45

13. A hospital bed comprising a frame; reticulated supporting fabric carried by said frame; a second frame mounted on said first 50 named frame and slidable transversely thereof; legs pivotally mounted on said second frame and adapted to be moved into position to support the outer edge thereof when projected laterally from said first named frame; pivoted links connected between said frame and each of said legs adapted when the leg is in supporting position to brace the leg in 55 position but adapted to be buckled with respect to each other for permitting the leg to be moved out of supporting position; a rod connecting the links of one leg with those of the other leg; a bracket mounted on said rod for providing a longitudinally 60 extending slot; crank means engaging said slot for moving said rod serving to actuate said links for carrying the legs into and out of supporting position; means for holding said crank against movement for holding the 65 legs out of supporting position; and reticulated supporting fabric carried by said second frame. 70

In testimony whereof I have signed my name to this specification in the presence of two subscribing witnesses.

AGNES R. LENZ.
